UNITED STATES PATENT OFFICE.

SAVILLION VAN CAMPEN, OF NEW YORK, N. Y.

DESIGN FOR MEDAL.

Specification forming part of Design No. 6,071, dated August 20, 1872.

Specification describing a new and original Design for a Medal, invented by SAVILLION VAN CAMPEN, of the city, county, and State of New York.

The accompanying drawing fully represents my new design.

This invention relates to a new design for a medal, which is made of leather or other appropriate material, and on which the profiles of President Grant and Senator H. Wilson

are displayed in bas-relief. The profile of President Grant shows the full head, and covers in part the head of Wilson, as shown.

I claim as my invention—

The design for a medal, as shown.
